ENCLOSED BELT HOLDER

Alexander F. Fleming, P.O. Box 364, Maywood, Ill.
Filed Dec. 22, 1958, Ser. No. 782,250
6 Claims. (Cl. 206—7)

The present invention relates generally to a holder to maintain articles in a sanitary, moth, vermin and dust-proof condition. More particularly, the instant holder is adapted to receive ladies' belts.

Briefly, the instant belt holder is comprised of a box type housing and a bag type housing with the buckles of the belts being adapted to be supported within the box type housing and with the strap portion of the belts being adapted to depend downwardly into the bag housing. Should a belt fall through into the bag, it may be removed by means of manipulation of the fastener to open the bottom of the bag.

An important object of the present invention is to provide a sanitary, moth, vermin and dust-proof receptacle for articles.

Still another important object of the present invention is to provide a sanitary, moth, vermin and dustproof receptacle for ladies' belts, particularly fabric belts.

Another important object of the present invention relates to the provision of a holder for articles such as fabric belts which holder may be manufactured with a minimum of cost.

Yet another object of the present invention relates to a belt holder which may be readily hung on a closet wall or a closet door.

According to the general features of the present invention there is provided a belt holder comprising a buckle housing structure and a belt housing structure, the buckle housing structure including rear and side walls and a swingable housing cover for opening and closing the buckle housing structure. The cover is pivotally supported between the side walls and is cooperable with the rear and side walls to define an enclosure. A series of transversely extending rods are supported between the side walls and are spaced with respect to one another to support the belt buckles thereon. The belt housing structure is comprised of a synthetic plastic bag depending below the buckle housing structure and has one end secured in assembly with the buckle housing structure for receipt of the portion of the belt extending below the buckle.

Other objects and features of the present invention will all more fully appear in view of the following detailed description taken in conjunction with the accompanying drawings illustrating therein a single embodiment, and in which:

FIGURE 1 is a fragmentary isometric view of the holder for articles such as ladies' belts;

FIGURE 2 is an enlarged fragmentary cross-sectional view, shown in full and dotted lines, taken substantially on the line II—II of FIGURE 1 looking in the direction indicated by the arrows;

FIGURE 3 is an enlarged fragmentary view, partially in section, showing the swingable cover locked in assembly with the side wall of the buckle housing;

FIGURE 4 is an enlarged cross-sectional view taken substantially on the line IV—IV of FIGURE 2 looking in the direction indicated by the arrows; and

FIGURE 5 is an enlarged fragmentary cross-sectional view taken substantially on the line V—V of FIGURE 1 looking in the direction indicated by the arrows.

As shown on the drawings:

The reference numeral 10 in FIGURE 1 indicates generally a holder which is adapted to receive articles such as ladies' belts, particularly fabric belts, as indicated at

2

11 in FIGURE 2. The belt holder comprises a buckle housing or a buckle housing structure 12 and a belt strap housing or belt strap housing structure 13 which are adapted to cooperate together to maintain the belts 11 in sanitary, moth, vermin and dust-proof condition.

The buckle housing structure includes a rear wall 14 provided with an attachment portion 14a which is equipped with spaced holes 14b to enable the housing structure to be screwed to a closet door or wall. The buckle housing 12 further has side walls 15 and 16 depending from the rear wall 14. Between the side walls 15 and 16 is a cover 17 which is in swingable pivotal assembly with the side walls 15 and 16 as indicated at 18. Preferably provided on the cover 17 are projections 17a such as is shown in FIGURE 4 which projections are lodged within grooves 15a and 16a provided on the side walls 15 and 16. Thus, the cover 17 is in pivotal assembly with the side walls 15 and 16 at the transversely opposite edges of the cover 17 by means of the engagement of the projections 17a within the grooves 15a and 16a which grooves are located on the side walls.

The cover 17 includes a vertical cover portion 17b which is the portion of the cover that is in pivotal assembly with the side walls 15 and 16. The cover 17 further includes a generally horizontal portion 17c which extends rearwardly towards the rear wall 14 with the cover having an edge 17d which is abutted against the rear wall attachment portion 14a when the cover is closed. To aid in the opening and closing of the cover 17, the cover 17 is provided with a handle grip 17e.

When the cover is closed relative to the side walls 15 and 16 the top surface of the cover lies flush with the angular top edges 15b and 16b of the side walls 15 and 16. Thus, it will be appreciated that transverse opposite edges 17f—17f transversely confront the side walls 15 and 16 when the cover is closed. In order to prevent the cover from collapsing when in a closed position, the cover 17 is provided with cover extensions 17g—17g and the side walls 15 and 16 are provided with notches defined by angular notch edges 15c and 16c. The tabs or extensions 17g—17g are fixedly engaged with the angular notch edges 15c and 16c when the cover is closed to resist accidental displacement of the cover.

The side walls 15 and 16 are provided with side wall hanger rails 15d and 16d which are formed integral with the side walls 15 and 16. These hanger rails are disposed at an inclined angle with respect to the side walls of the box so that different size buckles 11a may be disposed within the box. The rails 15d and 16d are provided with a series of sockets or recessed areas 15e and 16e. Disposed between the hanger rails 15d and 16d are suspension rods 19 with the opposite ends of the rods being carried within the recessed socket areas 15e and 16e to maintain the rods in assembly with the box.

The belt housing structure or bag 13 is suitably secured at 21 with the buckle housing structure 12. Since the buckle housing structure is preferably adapted to be manufactured from a suitable synthetic plastic such as polyethylene and further since the belt strap housing structure 13 is adapted to be manufactured from a synthetic plastic material such as clear vinyl and the like, the housing structures 12 and 13 may be joined together at 21 by a heat seal or by other suitable means. It has been found that where the buckle housing structure is manufactured from polyethylene that the side walls have some flexibility which more readily enables the cover and the suspension rods to be assembled in assembly with the side walls and the rear wall. Where the buckle housing is manufactured from a synthetic plastic material, the walls 14, 15, and 16 may be formed in a single die in unitary assembly together. Thereafter, the suspension rods 19 and the cover 17 are assembled between the side

walls 15 and 16. The handle 17e may be suitably secured or molded with the cover 17.

The belt strap housing structure 13 is provided with a strip type fastener structure 21 which may also be manufactured from a suitable synthetic plastic material. The fastener structure 21 includes strip sections 21a and 21b which are suitably secured in assembly with the bag 13 by a heat seal or the like, as is indicated at 22. The strip sections 21a and 21b are provided with a strip groove 21c and a strip extension 21d. The groove 21c and the extension 21d are of hook-like contour and are adapted to be pressed together in order to close the bottom of the bag 13 by maintaining the sections 21a and 21b in abutting relation with respect to one another. In order to open the bag 13 the fastener structure 21 is provided with tabs 21e—21e which tabs are secured to the sections 21a and 21b. By pulling the tabs 21e—21e apart the bottom of the bag may be opened so that if a belt should fall to the bottom of the bag it may be readily removed from the bottom end of the bag.

The instant holder structure 10 may have any suitable dimensions and is adapted to house other types of articles in addition to belts, such as other clothing garments.

To operate the holder 10 the cover 17 is pivoted at 18 relative to the side walls of the holder so that access may be gained to the interior of the holder. The belts 11 may then be inserted into the holder or removed from the holder as is desired. The rods 19 are adapted to support the belts 11 and the buckles 11a of the belts are adapted to be housed within the buckle housing structure 12. Strap portions 11b of the belt are for the most part adapted to be housed within the belt strap housing structure or bag 13.

The instant belt holder has been found to be a very satisfactory device for maintaining articles such as ladies' belts particularly fabric belts, in a sanitary, moth, vermin and dust-proof condition.

It will be understood that modifications and variations may be effected without departing from the scope of the novel concepts of the present invention.

I claim as my invention:

1. A belt holder comprising a rigid buckle housing structure and a flexible belt housing structure, the rigid buckle housing structure including rigid front, rear and side walls, a series of transversely extending rods supported on and between the rigid walls and spaced with respect to one another for superimposing and supporting the belt buckles of belts thereon, the belt housing structure comprising a flexible bag depending below the buckle housing structure and having one end secured in assembly with the walls of the buckle housing structure for receipt of the portion of the belt extending below the buckle, and a swingable housing cover overlying and spaced above the transversely extending rods enabling belt buckles to be supported therebetween, the cover being supported on and pivotally connected with the buckle housing structure, the cover being cooperable with the front, rear and side walls to define an enclosure and being pivotal relative to the walls so access may be gained into the buckle housing structure enabling belts to be mounted on and removed from the rods.

2. The belt holder of claim 1 further characterized by the flexible bag having fastener means at a bottom end of the bag to permit the bottom of the bag to be opened and closed.

3. The belt holder structure of claim 1 further characterized by the planes of the rods being disposed along an inclined plane within the enclosure to permit a greater range of different sized belt buckles to be mounted within the enclosure.

4. A belt holder comprising a rigid buckle housing structure and a belt housing structure, the rigid buckle housing structure including front, rear and side walls, the side walls having rod sockets, a series of transversely extend-

ing rods mounted in said sockets between the side walls and spaced with respect to one another for superimposing and supporting the belt buckles of belts thereon, the belt housing structure comprising a flexible bag depending below the buckle housing structure and having one end secured in assembly with the walls of the buckle housing structure for receipt of the portion of the belt extending below the buckle, and a swingable housing cover overlying and spaced above the transversely extending rods enabling belt buckles to be supported therebetween, the cover being supported on and pivotally connected with the buckle housing structure, the cover being cooperable with the front, rear and side walls to define an enclosure and being pivotal relative to the walls so access may be gained into the buckle housing structure enabling belts to be mounted on and removed from the rods.

5. A belt holder comprising a rigid buckle housing structure and a flexible belt housing structure, the rigid buckle housing structure including rigid front, rear and side walls, a series of transversely extending rods supported on and between the rigid walls and spaced with respect to one another for superimposing and supporting the belt buckles of belts thereon, the belt housing structure comprising a flexible bag depending below the buckle housing structure and having one end secured in assembly with the walls of the buckle housing structure for receipt of the portion of the belt extending below the buckle, and a swingable housing cover overlying and spaced above the transversely extending rods enabling belt buckles to be supported therebetween, the cover being supported on and pivotally connected with the buckle housing structure, the cover being cooperable with the front, rear and side walls to define an enclosure and being pivotal relative to the walls so access may be gained into the buckle housing structure enabling belts to be mounted on and removed from the rods, the rear wall having an attachment portion extending above the cover so fasteners may be extended through the attachment portion to mount the belt holder on a wall.

6. A belt holder comprising a rigid buckle housing structure and a flexible belt housing structure, the rigid buckle housing structure including rigid front, rear and side walls, a series of transversely extending rods supported on and between the rigid walls and spaced with respect to one another for superimposing and supporting the belt buckles of belts thereon, the belt housing structure comprising a flexible bag depending below the buckle housing structure and having one end secured in assembly with the walls of the buckle housing structure for receipt of the portion of the belt extending below the buckle, and a swingable housing cover overlying and spaced above the transversely extending rods enabling belt buckles to be supported therebetween, the cover being supported on and pivotally connected with the buckle housing structure, the cover being cooperable with the front, rear and side walls to define an enclosure and being pivotal relative to the walls so access may be gained into the buckle housing structure enabling belts to be mounted on and removed from the rods, the cover having a vertical cover portion forming a portion of the front wall and with the vertical cover portion being pivotally joined with the side walls to open and close the buckle housing structure.
